MOUNTING MEANS FOR IRONER SHOES

Thomas Harris, East Cleveland, Ohio, assignor to The Apex Electrical Manufacturing Co., Cleveland, Ohio, a corporation of Ohio

Application May 15, 1947, Serial No. 748,209

2 Claims. (Cl. 38—59)

1

This invention relates to ironing machines, and more particularly to an improved mounting and emergency release means for an ironing machine shoe.

It has been common practice in ironing machines wherein the shoe and roll are brought into ironing relation by power means to mount the shoe so that it can be manually moved away from the shoe in an emergency to prevent damage to an article being ironed or injury to an operator. For example, if the roll and shoe are in ironing relation and the power fails for any reason, an article being ironed would be damaged unless an emergency release means were provided. Also, the release means is used when it is desired to have sufficient clearance for cleaning the press face of the shoe. The manual release means in ironing machines wherein the roll and shoe are brought into engagement under power usually comprises a lever disposed beneath the base of the machine and at one side of the knee operating control to be accessible by one hand. However, in an emergency, it is awkward and time consuming to grope for a handle or emergency release which is infrequently used.

I provide a release means for an ironing machine of the above type comprising a bar normally extending above and along the shoe which is clearly visible and easily accessible to be pushed by either hand to release the shoe in an emergency. The shoe is normally locked to withstand the ironing pressure of the roll until the bar is manually pressed.

According to the invention, a bracket which resiliently supports the shoe is pivotally mounted on the ironing machine table and a generally U-shaped emergency release bar is disposed rearwardly of the shoe relative to the operator and normally extends above the shoe and for a substantial distance along the length of the shoe. This bar is mounted in association with the shoe bracket so that the shoe will be carried away from the roll when the bar is subjected to manual pressure, but will normally lock the shoe in a position to withstand roll pressure during ironing and pressing operations.

It is a primary object of the invention to provide improved mounting and emergency release means for an ironing machine shoe.

Another object of the invention is to provide a shoe mounting and emergency release means of the above type which positively locks the shoe in roll engaging position during normal operation.

Another object of the invention is to provide

2

a shoe mounting and emergency release means for an ironing machine of the type wherein the shoe and roll are engaged by power means and which is continuously visible to an operator and easily accessible and operable by either hand.

Another object of the invention is to provide a shoe mounting and emergency release means of the above type which comprises relatively few parts and is economical of manufacture.

10 Other objects of the invention and the invention itself will be clearly understood from a consideration of the following description and drawings, wherein:

Figure 1 is a perspective view of an ironing machine embodying the invention showing the shoe in normal or ironing position.

Figure 2 is an end elevational view of the ironing machine of Fig. 1 showing the shoe in released position.

20 Figure 3 is a fragmentary end elevational view of the shoe mounting and release means in normal position.

Figure 4 is a view generally similar to Fig. 3 showing the mounting and release means in released position.

25 Figure 5 is a front elevational view of the mounting and release means with a guard plate omitted for clearance of illustration, and

Figure 6 is an enlarged transverse section 30 showing the manner of securing the shoe to the mounting means.

Referring now to the drawings and particularly Figs. 1 and 2, I have illustrated the invention in association with a portable ironing machine having a base 10 which is adapted to be supported on a table or other suitable surface, but the invention is equally adaptable to various types of ironing machines wherein the roll and shoe are engaged under power and the manner of supporting the machine constitutes no essential part of the invention. The roll 11 is supported from a housing 12 fixed to the base 10, the roll being actuated in any suitable manner. The roll may be rotated and moved towards and from the shoe indicated at 13 by a motor disposed within the roll through a mechanism more fully described and illustrated in a co-pending application of Archibald H. Davis, Jr., Serial No. 688,663, filed August 6, 1946.

35 The emergency release and mounting means for the shoe 13 will now be described. Affixed to the top surface of the base 10, preferably by welding, is a support member 14 of generally elongate box form comprising a base 17, an upstanding back wall 18, an upstanding front wall 19, and up-

standing end walls 21. Pivoted to member 14 about an axis 22 is a bracket 23. Bracket 23 is preferably formed of sheet metal and comprises a curved back 24, side flanges 26, progressively increasing in width towards the base of the arm, and a top flange 21. Bracket 23 is preferably secured to member 14 by bolt and nut connections as indicated at 28 with bearing pads 29 being welded to end walls 21 of member 14.

A rock arm is pivoted to bracket 23 to rotate about an axis indicated at 31 and comprises a lower member 32 and a loop or U form bar 33 rigidly secured thereto, preferably by welding. Member 32 comprises a planar back 34, side flanges 36 preferably pin-connected to flanges 26 of bracket 23 and a top flange 37. The ends of bar 33 are preferably flattened and projected through grooves in side flanges 36 and secured to back 34 of member 32 by welding as previously indicated. Mounted on the lower end of flanges 36 are rollers 38 adapted to roll along base 17 of support member 14 as the rock arm is actuated. A pair of tension springs 39 are connected to member 32 and bracket 23 preferably by providing a loop in the flattened ends of bar 33 and bending over portions of side flanges 26 of bracket 23 as indicated at 40 to receive the opposite ends of the springs.

The shoe 13 which is of generally conventional construction is supported in the following manner. A pair of threaded studs 41 extend from the rear face of the shoe at spaced points and are guided through bushings 30 which are riveted to bracket 23. Compression springs 42 encircle the studs and seat within cup shaped depressions formed within bracket 23 and the back covering of the shoe, the spring force being maintained by nuts 43. If a relatively thick article is being ironed, the springs permit compensating movement of the shoe at somewhat increased pressure which is desirable for ironing such articles. A balancing spring 25 is provided to support the shoe when the roll is not in contact with the shoe.

Figure 6 illustrates the normal position of the shoe during ironing operations and it will be noted that the thrust on bracket 23 as the roll is brought into pressure engagement with the shoe is slightly upwardly or generally along the axis of studs 41. This thrust will tend to pivot bracket 23 about axis 22 and move axis 31 downwardly. However, since rollers 38 are in contact with the base 17 of support member 14, movement of bracket 23 is prevented. In other words, the position of axis 31 is such that the toggle action tending to rotate axis 31 in a counter-clockwise direction (Fig. 3) about axis 22 tends to increase the distance between axis 22 and rollers 38 which could only be effected if the rollers were free to move to the left, but this is prevented due to contact of back 34 of member 32 with the back wall 18 of support member 14.

In the event that the roll is in pressure engagement with the shoe and it is desired to quickly move the roll from engagement, it is only necessary to exert pressure on bar 33 and due to the fact that the horizontal portion of bar 33 is above roll 11 and is of substantial horizontal extent, it is easily accessible with either hand. A relatively slight pressure on the horizontal portion of bar 33 will pivot the rock arm about axis 31 and move the same to the position illustrated in Fig. 4. This movement carries bracket 23 and shoe 13 away from the roll 11 since bracket 23 is pin-connected to the rock arm at axis 31.

Springs 39 are increasingly stretched as the rock arm is moved in the release direction and effect a quick return of bracket 23 and bar 33 to normal or ironing position. When bar 33 is rocked clockwise (Fig. 4) until rollers 38 are to the left of a vertical plane through axis 22, the momentum and tension of springs 39 carries bracket 23 to the position shown in Fig. 3. Retraction of springs 39 carry bar 33 to the position of Fig. 3 and retains the bar in this position during normal ironing operation.

In order to prevent articles being ironed from passing into bracket 23, I preferably provide a guard plate 45 which is detachably secured to flanges 40 of arm 23, the guard plate having a lip 42 which extends over the top edge of front wall 19 of support member 14. In order to limit movement of bracket 23 and the rock arm in reverse direction, I provide a hook member 44 which is secured centrally of base 17 of support member 14 to engage the lower end of the rock arm as illustrated in Fig. 4.

It will now be understood that I have provided a mounting and emergency release means for an ironing machine shoe which will resiliently support the shoe to withstand the roll pressure during ironing operations and which can be operated to quickly move the shoe away from the roll by manual thrust on a bar extending longitudinally above the shoe.

I wish it to be understood that I do not desire to be limited to the exact details of construction shown and described, for obvious modifications will occur to a person skilled in the art.

What I claim is:

1. In an ironing machine of the type having a base, a shoe, and a roll movable towards and from the shoe under power, an emergency release and mounting means for the shoe comprising an open-top box-shaped structure affixed to the machine base, a bracket pivotally connected to the ends of said structure, a shoe mounted on the bracket, a rock arm pivoted to the bracket on an axis parallel to the bracket axis and intermediate the rear wall of said structure and the bracket axis, the lower portion of the rock arm engaging the structure base at a point substantially directly beneath the rock arm axis with the shoe in normal operating position whereby movement of the bracket due to roll pressure on the shoe will be prevented under operating conditions, and the rock arm being manually movable about its axis to move the lower portion of the rock arm towards the bracket axis whereby the bracket will be rotated around its pivotal axis due to its connection with the rock arm to move the shoe away from the roll.

2. In an ironing machine of the type having a base, a shoe, a roll, and power means for effecting relative movement of the roll and shoe towards and from each other, an emergency release and mounting means for the shoe comprising a bracket pivotally supported by the base on an axis spaced above the base and generally parallel to the roll axis, a shoe mounted on the bracket, a rock arm pivoted to the bracket on an axis parallel to the bracket axis and rearwardly thereof relative to the roll, the rock arm lower portion with the shoe in operating position engaging the base at a point substantially directly beneath the rock arm axis whereby bracket movement due to roll pressure on the shoe under operating conditions will be prevented, and the rock arm being manually movable about its axis to an inclined position whereby the bracket will

be rotated around its pivotal axis due to its connection with the rock arm to move the shoe away from the roll.

THOMAS HARRIS.
